UNITED STATES PATENT OFFICE.

JAMES GILBERT LANGDON, OF BALTIMORE, MARYLAND.

SECTIONAL TYPE-WRITER DESK.

1,110,948.

Specification of Letters Patent. Patented Sept. 15, 1914.

Application filed August 20, 1913. Serial No. 785,650.

To all whom it may concern:

Be it known that I, JAMES GILBERT LANGDON, a citizen of the United States, and a resident of the city of Baltimore, in the 5 State of Maryland, have made certain new and useful Improvements in Sectional Type-Writer Desks, of which the following is a specification.

My invention relates to improvements in 10 sectional typewriter desks, and it consists in the combinations, constructions and arrangements herein described and claimed.

An object of my invention is to provide a 15 desk for a machine, and one combined with it for holding supplies, such as stationery and the like, the latter being also capable of use as a writing desk for stenographic purposes.

A further object of my invention is to 20 provide a combined typewriter's and stenographer's desk of a novel form which consists of detachable sections so that the stenographer's desk can be placed on one side or the other of the typewriter's desk.

25 A further object of my invention is to provide a desk of the type described in which the various portions may serve as units for providing a number of stenographer's and typewriter's desks joined together so as to take up a minimum amount of space.

Other objects and advantages will appear 30 in the following specification, and the novel features of the device will be particularly 35 pointed out in the appended claims.

My invention is illustrated in the accompanying drawings, forming part of this application, in which—

Figure 1 is a perspective view showing 40 one embodiment of my invention; Fig. 2 is a plan view thereof; Fig. 3 is a bottom view; Fig. 4 is a vertical section view; Fig. 5 is a plan view showing a different arrangement of parts; and Figs. 6, 7 and 8 are plan views of modified arrangements.

In carrying out my invention I provide 45 an oblong desk or table portion for holding a typewriting machine. In Fig. 1, I have denoted this portion by the character 1. It is provided with pigeon holes 2 for the 50 reception of papers or other articles. The top 3 is provided with a back rail 4 and with an end rail 5.

The writing desk proper comprises a body 55 portion 6 having a top 7 and being provided with a drawer 8. The stenographer's

desk or writing desk is arranged at right angles to the typewriter's desk, the two desk portions forming a unitary L-shaped structure, as clearly shown in Fig. 2. In order to secure the two desk members together I provide a retaining member 9. This consists preferably of a board which may be secured to the bottom of the frame members of the two desk portions by means of screws 60 65 10. This holds the desk portions firmly together.

The desk portion 1 is provided at one end with a dove-tailed socket formed between two lugs 11. This socket is arranged to receive a leg 12 which is held to the frame of the table member 1 by means of a removable bolt 13 and winged nut 14.

One end of the higher table 6 is provided with similar lugs 11^a between which a leg 15 is held by means of a bolt 16. At the opposite end of the desk member 6 is secured a detachable leg 20 which is arranged centrally of the desk member as shown in Fig. 3. This provides three legs for the 70 75 80 structure and thus the device will be able to set evenly on an uneven floor.

From the foregoing description of the various parts of the device, the operation thereof may be readily understood. In Fig. 85 2 I have shown the desk for the typewriter as being disposed on one side of that for the supplies or the writing desk. The position of the machine is shown in dotted lines at 17, while the typewriter's chair is shown at 18. 90

Now if it is desired to place the typewriter's desk 1 on the opposite side of the higher table, it is only necessary to remove the retaining board 9, the end rail 5 and the leg 12, place the desk 1 on the opposite side 95 and fit the leg 12 into the socket formed by lugs 11^a shown in dotted lines in Fig. 3, at the opposite end of the desk section, and secure the end rail in place. The retaining board 9 is then reversed and fastened to the 100 underside of the two desk portions. This results in the formation of a desk like that shown in Fig. 5.

It is sometimes desirable to have a writing desk on each side of the typewriter's 105 desk, and to this end a second desk, such as the desk 6^a in Fig. 6 may be added.

It will be obvious that the idea of the sectional desk may be further carried out by the use of lower desks or tables such as 110 those shown at 3, 3^a, and 3^b in Fig. 7, alternating with the higher desks or tables such

as those shown at 6 and 6^a. This arrangement is especially adapted for use in chemical, biological or botanical laboratories. The lower desk or table is at a correct height 5 for microscopes to rest upon during research work, while the higher des's are at the right height for writing or taking notes.

It is obvious that other arrangements than those shown might be made without departing from the spirit of the invention.

I claim;

1. In a sectional typewriter desk, a pair of table members, one of said table members being disposed below the other and being 15 detachably secured to the other on either side thereof, said lower table member being provided with a detachable leg and a detachable end rail adapted to be placed at the opposite end of said lower table member, 20 reversible means secured to the bottom of said table members for securing the two

table members together and a pair of legs for one of said table members.

2. In a sectional typewriter desk, a rectangular oblong table member provided 25 with a side and an end rail, a raised table member disposed at right angles to said first named table member, a connecting member adapted to be secured to the bottoms of both of said table members for holding them together, said connecting member being reversible so as to permit of attachment of the oblong member on either side of said raised table member, said oblong table member being provided with sockets at both ends and 30 having a table leg arranged to enter either of said sockets, and a pair of legs secured to said raised table member.

JAMES GILBERT LANGDON.
